UNITED STATES PATENT OFFICE

JACOB RAFFELSON, OF ROCHESTER, NEW YORK

DISPLAY BOARD

Application filed August 10, 1927. Serial No. 212,029.

This invention relates to a display board, more particularly for displaying shirts in windows or on the counters of stores, and has for its principal object to provide a simple and effective mechanism for holding a folded shirt in proper position flatwise upon the board.

Another object of the invention is to provide holding mechanism of such a nature that it will not injure the shirt, thus allowing the shirt to be sold as readily after being displayed as before.

A further object is to provide a board to which a shirt may be quickly attached or removed and with a minimum of effort.

Still another object is to provide means for holding the shoulders of a shirt while the body of the shirt is being stretched over the board and clamped.

With these and other ends in view, the invention comprises the structure and combination of parts which will appear more clearly from the following description when read in conjunction with the accompanying drawings, the novel features being pointed out in the claims following the description.

In the drawings:

Figure 1 is a rear elevation of a shirt display board, showing one possible embodiment of my invention applied thereto;

Fig. 2 is a side elevation thereof;

Fig. 3 is a section taken approximately along the line 3—3 of Fig. 1, illustrating the action of the clamping mechanism in holding a shirt on the board, and

Fig. 4 is a section taken approximately along the line 4—4 of Fig. 1, showing the clamping mechanism in open position.

In the conventional shirt display boards commonly used in stores at the present time, it is customary to attach a shirt to the board by means of pins. This method of attachment injures the shirt, by making pin holes in the fabric thereof. If the shirt be pulled a little too hard while being placed on the board, the pins are very apt to tear it. After being displayed on boards, shirts must nearly always be sold at a reduced price, on account of the damage which has been done to them.

This is especially true of silk shirts, since the

fabric of which they are made is more apt to tear, and the pin holes are more objectionable. In fact, many stores make a practice of never placing a silk shirt on a display board.

Furthermore, aside from the important question of injury to the shirt, the conventional display boards are unsatisfactory from a standpoint of time and skill required to place a shirt upon the board. Only an experienced person can so place a shirt on the board that it will have a neat and attractive appearance thereon, and even a person of considerable experience requires a comparatively large amount of time for completing the operation.

As distinguished from this known construction, my novel shirt display board comprises a mechanism for holding the shirt upon the board without injury to the fabric. It is not necessary to make pin holes or other perforations in the cloth when shirts are held on the board by means of my invention, and silk shirts may be attached to the board without fear of damage.

In addition to this important feature of obviating damage to the goods, my invention also is of such a nature that it allows a shirt to be placed upon the board by a comparatively inexperienced person, and furthermore, the operation may be performed quickly, thus saving a great amount of time heretofore necessary in dressing windows or otherwise displaying merchandise.

This novel shirt display board has a main body portion 10 which may consist of any suitable material, such as wood, metal, cardboard or composition board. On the back of this board and near the top edge thereof is a suitable catch or clip 11 for retaining the board on a stand or support of the conventional kind. The body of this board may be of any suitable size or shape, preferably rectangular, such as the display boards now in common use. Ordinarily, but not necessarily, the board is considerably longer than its width. A part of the length has been broken away and omitted in Figures 1 and 2 so as to condense the drawing.

On the back of this board is mounted a suit-

able clamping mechanism for holding the shirt. It is understood that in using the board, the front portion of the shirt is displayed on the front of the board, and the sides and tail of the shirt are brought around the edge of the board and clamped on the back so that the clamping mechanism is entirely out of sight. Many different forms of clamping mechanism could be used for this purpose. The drawing illustrates one possible form of clamp which includes a generally rectangular frame 12. This frame may be formed integrally with the body of the board or it may be made of strips of any suitable material screwed, riveted, glued or otherwise fastened to the surface of the board.

Suitable mechanism is provided for co-operation with this frame 12, so that the shirt may be held between this mechanism and the frame. One possible form of such co-operating mechanism consists of the bails 13 and 14, these bails being pivoted to the frame 12 near the center of the board at 15 and 16, as shown in Figs. 1 and 4. The bail 13 is arranged to cooperate with the right hand half of the frame 12 (as seen from the back of the board, as in Fig. 1), and the bail 14 cooperates similarly with the left half of the frame. As will be seen from the drawings, the inside dimensions of the bail are slightly larger than the outside dimensions of the frame so that a slight space is provided between the edge of the bail and the edge of the frame when the two are brought into cooperative relationship. This space is so designed when constructing the mechanism that it will be approximately as wide as the thickness of two layers of fabric. Consequently, the sides of the shirt, having been brought around the edges of the display board, may be inserted between the frame and the bails when the bails are in their open position, shown in Fig. 4, and the bails may then be moved until they are in the plane of the frame, thus clamping the shirt between the frame and the bails.

For holding the tail of the shirt after it has been brought around the bottom of the display board, separate means are provided. A cross piece 17, of approximately the same height as the members 12, is placed across the frame at a suitable distance above the bottom thereof. A member 18 is pivoted at one end as at 19, to one of the bails, and carries at its other end a device for attaching it to the other bail, which device may be in the nature of a thumb screw 20 adapted to be screwed into a threaded opening in the bail. It will be understood that the opening in the bail and the pivot 19 are so placed that when the bar 18 is connected to the bails, as shown in Fig. 1, it overlies the cross piece 17 above mentioned. This cross piece does not appear in Fig. 1 since it is entirely hidden by the member 18. When it is desired to open the clamping

mechanism to receive a shirt, the thumb screw 20 is unscrewed and the member 18 is dropped down until it hangs vertically from its pivot 19, this position being shown in dotted lines labelled 21 in Fig. 1. When the sides of the shirt have been clamped, the tail of the shirt is then brought up and held over the cross piece 17 while the member 18 is swung up to its horizontal position and fixed there by means of the thumb screw, thus clamping the tail of the shirt between the cross piece 17 and the member 18. In order to assist in getting the thumb screw 20 correctly aligned with the threaded opening into which it is to be screwed, a stop member 22 may be formed on the bail, as shown in Fig. 1, so that when the end of the member 18 is brought into contact with the stop 22, the thumb screw 20 will then be correctly aligned with its threaded opening.

The mechanism so far described clamps the sides and tail of the shirt. In order to assist in holding the shirt while it is being clamped upon the board, it is very desirable to have some mechanism for holding the shoulders thereof. Such mechanism may be of many forms, one possible embodiment thereof consisting of the spring clips 23 and 24, shown in Figs. 1 and 2. It will be readily apparent from Fig. 2 that pressure on one end of one of these clips will raise the other end, and when the pressure is released, the spring in the clip will force the other end against the board, thus holding anything which has been placed under the end.

The mode of using this shirt display board will now be described. A folded shirt is spread smoothly over the face of the board in such a position that the shoulders thereof are slightly above the top edge of the board. These shoulders are then folded over the edge and held by means of the clips 23 and 24. The thumb screw 20 is then unscrewed, allowing the bar 18 to drop down to the position 21, which allows the bails 13 and 14 to be opened as shown in Fig. 4. The sides of the shirt are then brought around the sides of the board and placed between the bails and the frame members 12. The bails are then closed or brought into the same plane as the frame 12, which results in clamping the shirt fabric firmly between the bails and the frame. This position is illustrated in Fig. 3, in which the position of the layer of fabric 25 is clearly shown. It will be seen that the fabric is clamped between two surfaces which are perpendicular to the face of the board, and it is further apparent that there is no tendency whatever for a pull on the fabric to open the clamping mechanism. On the contrary, if the fabric 25 is pulled, it will tend to move the bails still closer to the surface of the board, on account of the friction between the bails and the fabric. Thus the tighter the cloth is pulled, the greater will be the tendency for the clamping mechanism to stay closed, and

it is not necessary to provide any catch or other device to hold the bails in proper position.

After the shoulders and sides of the shirt have been clamped in the manner above described, the member 18 meanwhile being in the position 21, the tail of the shirt is then brought up around the bottom of the board and placed over the cross bar 17, as has been described above. The free end of the member 18 is then brought up until it comes in contact with the stop 22 and the thumb screw 20 is screwed into its threaded opening, thus clamping the tail of the shirt effectively. It should be noted that the member 18, in addition to clamping the tail of the shirt, acts also to hold the bails 13 and 14 in position so that they will not become displaced accidentally when the board is being handled while placing it in the window or on the counter of the store. It is apparent that the bails cannot move out of the plane of the frame 12 to any appreciable extent as long as the member 18 extends across between the bails, in its Fig. 3 position.

While one embodiment of the invention has been disclosed, it is to be understood that the inventive idea may be carried out in a number of ways. This application is therefore not to be limited to the precise details shown, but is intended to cover all modifications thereof falling within the spirit of the invention or the scope of the appended claims.

I claim:

1. The combination with a shirt display board, of a rectangular frame on one side of said board, a bail pivotally connected to said frame at the top and bottom thereof and adapted to be moved to and from a position in which it is in the plane of said frame and slightly spaced from one side of the frame, a second bail similarly pivoted and having a similar relationship to the other side of the frame, a cross-piece pivoted at one end to one of the bails, and means for attaching the other end of said cross piece to the other of said bails.

2. A display board for holding a folded garment stretched over the front thereof comprising clamping mechanisms mounted on the back of the board for engaging the sides of the folded garment at points between the side edges of the board, and separate clamping means mounted on the back of the board for holding the tail portion of the folded garment, the latter being extended around the edges of the board from front to back to permit engagement by said clamping means.

3. A display board for holding a folded garment stretched over the front thereof comprising a pair of clamping bails pivotally mounted on the back of the board to swing about a longitudinal axis of the board for engagement with the side portions of the folded garment, and fixed clamping walls on

the back of the board for cooperation with the clamping bails, the sides of said bails being spaced between the sides of the board and the ends of the bails being spaced between the ends of the board.

4. A display board for holding a folded garment stretched over the front thereof comprising clamping walls fixed on the back of the board, clamping bails pivotally mounted on the back of the board and cooperating with said fixed clamping walls, and tail clamping means comprising a cross piece pivotally mounted upon one of said bails and engageable with the other of said bails, acting to hold the tail portion of the folded garment down between the bails.

5. A display board for holding a folded garment stretched over the front thereof comprising mechanism for clamping the sides of the folded garment on the back of the board, said clamping mechanism including a frame secured to the back of the board and spaced inwardly from its outer edges, and separate clamping means also mounted on the back of the board for holding the shoulder portions of the garment.

6. A display board for holding a folded garment stretched over the front thereof comprising mechanism for clamping the sides of the folded garment on the back of the board and including a pivoted member adapted to engage the garment at a point between the side edges of the board, separate clamping means mounted on the back of the board for holding the tail portion of the garment, and separate clamping means also mounted on the back of the board for holding the shoulder portions of the garment.

In witness whereof, I have hereunto signed my name.

JACOB RAFFELSON.
